LEONARD WINTER HOLME, OF BOWRAL, NEW SOUTH WALES, AUSTRALIA

LOADING APPARATUS

Application filed March 31, 1931, Serial No. 526,635, and in Australia November 19, 1930.

The invention relates to loading materials upon motor lorries and the like and provides apparatus for the purpose wherein the load is raised to the required height by pressure exerted by the vehicle when backing in to receive the load or alternatively by a winch forming part of the apparatus.

According hereto a frame having foundation plates adapted to lie upon the surface of the ground, has side members between which is a runway for the vehicle.

The load to be raised is placed in a hopper the bottom of which normally is at ground level and which is connected by suspension arms to cross bars which are journaled at their ends in the upper ends of lifting levers.

There is a pair of lifting levers upon each side of the apparatus and the members of each pair are preferably of the same length, crossing each other and assuming relatively varying angles as the load is raised.

One end of a member of each pair of lifting levers is hinged to the outer end of the frame while the ends of the other levers are journaled upon the spindles of rollers which run upon guides carried upon, or formed by, the foundation plates.

Connecting rods connect the spindles of each of the rollers with guide sheaves running upon longitudinal horizontal guides forming part of the frame and the spindles of the guide sheaves are connected by side rods with a striking bar extending across the frame and adapted to be pressed against by a vehicle backing into the runway.

Rearward movement of the striking bar, under pressure of the vehicle, causes the load to be raised by the lifting levers.

To provide for cases where it is not convenient to use the rearward motion of the vehicle to raise the load, for instance for loading horse drawn vehicles, and also to sustain the hopper, and, to lower it when the vehicle is withdrawn, wire ropes operated by a winch are employed as hereinafter described.

I will now describe my invention in detail by aid of the accompanying drawings wherein:

Fig. 1 is a side elevation showing the apparatus in position before the load is raised. 50

Fig. 2 is a corresponding plan and

Fig. 3 a side elevation showing the apparatus with the load raised.

Fig. 4 is a perspective view of a striking bar arrangement. 55

The frame of the apparatus is comprised of parallel foundation plates 1 connected by cross ties 2. Upon each side are the vertical standards 3 which support the respective horizontal guide rails 4 the inner ends of which are curved upwardly for a purpose herein-after described. Runners 4a for the wheels of the vehicle are carried upon the cross ties 2.

Corresponding pairs of lifting levers comprised of the members 5 and 6 are employed upon each side of the apparatus. The levers 5 are pivoted at their lower ends 7 upon the foundation plates of the frame while the lower ends of the levers 6 are provided with flanged rollers 8 which run upon the foundation plates. 65

Connecting rods 9 journaled upon the lower ends of levers 6 are provided at their upper ends with flanged guide sheaves 10 which run upon the respective guide rails 4. 70

Side rods 11 are journaled at one end upon the spindles 12 of guide sheaves 10 and at their opposite extremities are connected to a striking bar 13 which extends from side to side of the apparatus in such position that it is struck by the rear end of a vehicle 14 when it is backed in to receive its load. 75

Lifting levers 5 and 6 cross each other and their respective upper ends are journaled at 15 and 16 upon the ends of a cross bar 17. 80

A hopper 18 is connected to the cross bars 17 by the pairs of swing arms 19 which, at their upper ends, are pivoted to the middle of the respective cross bars upon arbors 20 90

which work in vertical guide slots 21 formed in brackets 22 projecting upwardly from the sides of the hopper.

The swing arms have longitudinal slots 23 which receive pins 24 projecting from the sides of the hopper.

A hook bar 25 hinged upon the hopper at 26 has a hooked end 27 which is passed over the journal spindle 15 of one of the cross bars 10 to hold the hopper in horizontal position until it is desired to tip its load, when by releasing the hook the hopper may be tilted into the position shown in dotted lines Fig. 3 or the tilting of the hopper may be effected by 15 rearward movement of the vehicle as herein-after described.

Ropes 28 and 29 one upon each side of the apparatus are at their respective ends fastened to the axles of the rollers 8.

20 The rope 28 passes around a guide sheave 30 and from thence is led beneath another guide sheave 31 to the barrel 32 of a winch which is fixed to the standards of the frame.

Rope 29 passes around guide sheave 48 and 25 beneath guide sheave 49 to the winch barrel 32. Both ropes 28 and 29 being coiled around the winch barrel in the same direction. The guide sheave 48 is located beneath the runways 4a so as to be clear of the wheels 30 of vehicle 14.

The winch is of ordinary construction having turning handles 33, gear wheels 34, hand brake 35 and ratchet wheel 36 engaged by a pawl 37.

35 Another rope 38 is secured at its end to the winch barrel 32 around which it is wound in opposite direction to ropes 28 and 29, it then passes beneath a guide sheave 39 around another guide sheave 40 and is connected to the 40 axle of roller 8 upon the same side of the apparatus.

To prevent the side rods 11 from turning down beyond a certain limit when the striking bar is not in contact with the back of a 45 vehicle, bearer brackets 42 are fixed to each of the connecting rods 9.

Striking bar 13 is pivoted at one end upon one of the side rods and at its opposite end 50 has a hook 43 which hooks over the end of the side bar opposite between collars 44 and 45 thereon, as shown in Fig. 4.

To prevent the guide sheaves 10 from rising from the guide rails 4 arms 46 swinging from the spindles 12 of the guide sheaves each 55 carry a roller 47 which runs beneath the guide rail.

In operation the hopper will be loaded while the parts are in position, shown in Figs. 1 and 2. The vehicle is then backed in and 60 by contact with the striking bar pulls the side rods towards the hopper.

The lifting levers 6 being pushed by the connecting rods cause the cross bars 17 to rise until their arbors 20 reach the ends of the 65 slots 21 in the brackets 22.

Continued movement of the vehicle then raises the hopper sufficiently high to clear the end of the vehicle.

Guide sheaves 10 will at that stage be at the end of the horizontal portion of guide 70 rails 4.

Further rearward movement of the vehicle causes guide sheaves 10 to pass up the curved extensions of the guide rails. The connecting rods therefor have no further effect upon 75 the ends of levers 6 and the vehicle may be backed beneath the load.

When it is desired to back the vehicle further the hook at the end of the striking bar is released from the side rod, and the bar 80 swings clear of the vehicle.

Rearward movement of the vehicle causes rope 38 to be pulled and the winch barrel 32 thereby rotated, ropes 28 and 29 being wound upon the barrel while rope 38 unwinds from 85 it.

The pawl 37 by engagement in the ratchet wheel 36 prevents rotation of the winch drum in one direction and the hopper is therefore sustained until the pawl is released from the 90 ratchet wheel, when by using the hand brake 35 the hopper may be lowered to its normal position.

It will be obvious that by using the winch the hopper may be raised without utilizing 95 the rearward movement of a vehicle.

To facilitate tilting of the hopper to discharge its load the movement of levers 5 is limited by chains 49 secured at one end to the lever and at the other end to the foundation 100 plates 1.

Continued rearward movement of the vehicle beyond the position shown in the drawings will affect levers 6 only, and, through the cross bars 17, the hopper will be tilted 105 into a convenient position for the deposit of its load.

I claim:—

1. Apparatus for the purpose set forth comprising in combination a frame, a runway 110 for a vehicle therein, two corresponding pairs of lifting levers one pair upon each side of the frame, a hopper, cross bars journalled upon the upper ends of the lifting levers and suspension arms connecting the hopper thereto, hinge means connecting one member of each pair of lifting levers to the frame, foundation plates for the frame, rollers running thereon, spindles for the rollers upon which a member of each pair of lifting arms 115 is journalled, longitudinal guides upon the frame, guide sheaves running thereon, connecting rods connecting the spindles of the rollers with the spindles of the guide sheaves, a striking bar extending across the frame, 120 and side rods connecting the guide sheaves with the ends of the striking bar as described.

2. Apparatus for the purpose set forth comprising in combination a frame, a runway 125 for a vehicle therein, two correspond- 130

- ing pairs of lifting levers one pair upon each side of the frame, a hopper, cross bars journaled upon the upper ends of the lifting levers, suspension arms connecting the hopper thereto, hinge means connecting one member of each pair of lifting levers to the frame, foundation plates for the frame, rollers running thereon, spindles for the rollers upon which a member of each pair of lifting arms is journaled, longitudinal guides upon the frame, guide sheaves running thereon, connecting rods connecting the spindles of the rollers with the spindles of the guide sheaves, ropes connected to the spindles of the rollers, guide sheaves for the ropes, a winch, a barrel thereof around which the ropes are coiled, another rope coiled upon the winch barrel in opposite direction to first mentioned ropes and connected at its end to the spindle of one of said rollers as specified.
3. Apparatus for the purpose set forth comprising in combination a frame, a runway for a vehicle therein, two corresponding pairs of lifting levers one pair upon each side of the frame, a hopper, cross bars journaled upon the upper ends of the lifting levers and suspension arms pivotally connecting the hopper thereto, hinge means connecting one member of each pair of lifting levers to the frame, foundation plates for the frame, rollers running thereon, spindles for the rollers upon which a member of each pair of lifting arms is journaled, longitudinal guides upon the frame, an upwardly curved extension from each guide, guide sheaves traversable upon the guides and extensions thereof, connecting rods connecting the spindles of the rollers with the spindles of the guide sheaves, a striking bar extending across the frame, and side rods connecting the guide sheaves with the ends of the striking bar.
4. In apparatus for the purpose set forth in combination two corresponding pairs of lifting levers, hinge means in fixed location for the end of a member of each pair, rollers one upon the end of a member of each pair, a hopper, cross bars pivotally connecting the upper ends of the respective pairs of levers, suspension arms connecting the hopper to the cross bars, with means for traversing the rollers whereby the hopper is lifted and lowered.
5. In apparatus for the purpose set forth in combination two corresponding pairs of lifting levers, hinged means in fixed location for the end of one member of each pair, rollers one upon the end of another member of each pair, a hopper for the upper ends of the lifting levers, means for traversing the rollers and means for limiting the movement of the hinged members.
6. In apparatus for the purpose set forth in combination two corresponding pairs of lifting levers, hinged means in fixed location for the end of a member of each pair, rollers one upon the end of another member of
- each pair, a hopper, brackets upon the hopper having guide slots, arbors upon the hopper working in the guide slots, a cross bar pivoted upon the arbor, pivotal means for connecting the ends thereof to the upper ends of the lifting levers, swing arms pivotally connected to said arbor and having longitudinal slots, pins projecting from the hopper engaging in the slots with means for traversing the rollers whereby the hopper is lifted and lowered.
- In testimony whereof I have signed my name to this specification.
- LEONARD WINTER HOLME.
